UNITED STATES PATENT OFFICE.

GEORGE S. RODD, OF HOUGHTON, MICHIGAN.

SWING.

1,247,577.

Specification of Letters Patent. Patented Nov. 20, 1917.

Application filed October 25, 1916. Serial No. 127,634.

To all whom it may concern:

Be it known that I, GEORGE S. RODD, citizen of the United States, residing at Houghton, in the county of Houghton and State of Michigan, have invented certain new and useful Improvements in Swings, of which the following is a specification, reference being had therein to the accompanying drawing.

10 The invention relates to improvements in a convertible back, particularly adapted for swings, porch hammocks, settees and the like, although capable of application to chairs or wherever a convertible back may 15 be desirable.

The object of the invention is to provide a swing, chair or other device with an adjustable back, which may be readily converted into a canopy or shading means for 20 the seat.

A further object of the invention is to provide simple and efficient means for maintaining the back in an inclined, vertical or horizontal position with reference to the 25 seat, so that if the occupant desires the back can be readily shifted from a vertical to other positions to protect the occupant from the sun rays, wind or other elements. It will of course be understood that as the position of the sun and wind changes, the convertible back may be accordingly adjusted and retained in its adjusted position at all 30 times to protect the occupant.

Another object of the invention is to provide a seat, swing, hammock or the like with an adjustable back, capable of not only being converted into a canopy and protector, but also one which is adapted to be shifted from one extreme side of the device 40 to the other, as may be desirable.

In the accompanying drawings I have disclosed the preferred embodiment of my invention in which the convertible back is disclosed as being attached to a porch swing or 45 hammock, but it will of course be understood that the device is capable of application wherever desired, and that many changes in the arrangement and construction of the parts can be made without de- 50 parting from the invention.

In the drawings:

Figure 1 is a view looking at one side of the swing.

Fig. 2 is a front elevation; and,

55 Figs. 3 and 4 are detail views.

Referring now more particularly to the

drawings, wherein like reference characters indicate corresponding parts, the numeral 1 designates a swing seat, preferably of the upholstered type suspended by means of 60 standards 2 arranged on each side thereof and supporting chains 3 attached to said standards and to suitable portions of the swing. This is a well known and approved means of supporting a swing, but I wish it 65 to be understood that any other supporting means may be employed if desired. The frame of the swing is preferably composed of metallic frame bars and is conveniently upholstered.

Extending across each end 4 and secured to the vertical portions thereof by bolts 5 are the cross bars 6 having double arc portions 7 joined by intermediate portions carrying inwardly disposed pivot pins 8, 75 and providing a narrow space between the adjacent ends of the arc portions for a purpose which will hereinafter appear. While it is preferable to dispose one of the bars 6 upon each end of the frame this is not 80 absolutely necessary as good results can be obtained with the use of but a single bar attached to one end of the swing seat. The bars 6 have arranged within the curved edge portions thereof suitable open ended sockets 85 9 for retaining the convertible back to be presently described in different adjusted positions. Any number of these sockets may be employed or any other equivalent retaining means may be utilized.

The swing is provided with a convertible back 10 of any suitable design having fixedly attached thereto on each end intermediate its sides, slotted arms 11, which are of a substantial length. The pivot pins 8 carried by the bars 6 are disposed within the elongated slots 11' in the swinging arms 11 and constitute a pivot for the convertible back and upon which the said back is turned.

The bars 6 have attached thereto intermediate their ends and between the arc portions thereof metallic brackets 12, rigidly fitted to the arms extending below the said bars and provided with inwardly rebent portions 13 having sockets 14 therein, for receiving pins 15 carried by the lower ends of the slotted arms 11 for maintaining the back in its elevated or horizontal position as disclosed in full lines in Fig. 1. When the back is to be converted into a canopy by elevating 110 the same the arms 11 are moved outward and swung on their pivots 8 until they oc-

cupy an elevated or vertical position and are then slightly lowered, so that the pins 15 carried thereby enter the sockets 14 within the rigid rebent portions 13 of the brackets 5 which prevent any swinging movement of the arms, thereby maintaining the back in a horizontal position over the seat to protect the same from rain, sun rays or the like.

When the back is to be moved from its 10 elevated position to its normal position, that is vertically disposed, to constitute a back rest for the occupant, the slotted arms 11 are moved on the pivots 8, and the pins 15 carried thereby having been disengaged from 15 the sockets 14 are shifted so that the said pins engage the outermost sockets 9 in the bars 6, at which time the arms 11 are disposed in a substantially horizontal plane. The back may be adjusted so as to occupy 20 any inclined position to properly shade the seat by shifting the arms 11 and placing the pins 15 carried thereby into the proper one of the intermediate sockets in the lower surfaces of the arc portions 7, it being observed 25 that the sockets are disposed in different vertical planes to allow the back to be retained wherever desired. In the drawings I have disclosed the back as being held in an inclined position by having the pins 15 30 carried by the lower ends of the arms 11 within the intermediate sockets in the right hand arc portions of the bars 6. It will be obvious that any number of notches for holding the convertible back in its adjusted positions may be employed, and that by maintaining the back in an inclined as well as a vertical or horizontal position the seat can be shaded at all times irrespective of the 35 position of the sun. When the back is converted into a canopy the cool breezes can also pass through the swing adding greatly to the comfort of the occupant. The back when converted into a canopy is primarily adapted for shading the seat, but it will, of 40 course, be understood that the same will also protect the occupant from rain, mist, wind or other undesirable elements, as well as from the hot sun rays.

It is often desirable for the occupant to 50 face in different directions, and to this end the back 10 is shiftable so that the same can be swung from one extreme side of the seat to the other upon the arms 11. In the drawings the back is disclosed as being positioned 55 on the left hand side of the seat, but it will, of course, be seen that by the double arc formation of the bars 6, the back 10 may be shifted on the right side of the seat upon the swinging of the arms 11, so as to occupy any 60 inclined or vertical position relative to this side of the seat.

From the foregoing it will be manifest 65 that the convertible back is capable of being maintained in any inclined position relative to the seat upon the proper adjustment of

the arms 11, in view of the fact that the bars 6 are provided with a plurality of sockets disposed in different vertical planes coöperating with the pins 15 carried by the bars 11. The slotted arms also permit the back when 70 converted into a canopy or protecting means for the seat to be raised a considérable distance therefrom which is particularly desirable, while the back is moved toward its pivot point and the seat when the same occupies a vertical position. 75

The convertible back is capable of being maintained in an inclined position in view of the specific formation of the bars 6 having double arc portions providing curved 80 surfaces in which there are disposed sockets for receiving the pins 15 carried by the side rods, but while this structure is highly efficient and desirable any other approved means for accomplishing the desired end 85 may be used without departing from the invention. The bars 6 have the double arc portions to permit the back to be supported on either side of the seat in any inclined position relative thereto, but only one curved 90 portion is needed if the back is to be adjusted relative to the seat on only one side thereof.

Having thus described the invention, what I claim is:

1. In a device of the character described, the combination with a seat, a back therefor, a bar having double curved portions attached to said seat, means for pivoting the back to the seat comprising an arm having 100 a slot therein receiving a pivot pin carried by said curved bar, a plurality of separated engaging portions disposed within said bar, and a part carried by the back supporting arm adapted to coöperate with any one of 105 said engaging portions for maintaining the back in a vertical, or other position above the seat to constitute a protecting means therefor.

2. In a device of the character described, 110 the combination with a seat, of an adjustable back therefor, a slotted member connected with said back, a retaining device carried by the seat and provided with a portion disposed within the slot in the back 115 carrying member for pivotally mounting the same, said retaining device being provided with portions coöperating with a part carried by the slotted member located in different vertical planes for maintaining the 120 back in various elevated positions whereby the same may constitute a protector for the seat.

3. In a device of the kind described, the combination with a seat, an adjustable back 125 therefor, means for supporting said back including a member carried thereby, a retaining device having engaging portions located in different vertical planes coöperating with a part carried by the back support for main- 130

taining the back in its different positions, and means for positively holding the back in one position comprising a bracket carried by the retaining device and having a rebent 5 portion provided with a socket receiving a part carried by the back support.

4. In a device of the character described, the combination with a seat, a back therefor, a retaining device attached to the seat, means 10 for pivoting the back to the seat comprising an arm having a slot therein receiving a pivot pin carried by the retaining device, a plurality of separated engaging portions disposed within the retaining device on each 15 side of the pivot pin, and a part carried by the back supporting arm adapted to coöperate with said engaging portions for maintaining the back in various elevated positions.

20 5. In a device of the character described,

the combination with a seat, a back therefor, a retaining device attached to the seat, means for pivoting the back to the seat comprising an arm having a slot therein receiving a pivot pin carried by the retaining device, 25 a plurality of separated engaging portions disposed within the retaining device on each side of the pivot pin, and a part carried by the back supporting arm adapted to coöperate with said engaging portions 30 for maintaining the back in various elevated positions, the said engaging portions being located in different vertical planes.

In testimony whereof I hereunto affix my signature in the presence of two witnesses. 35

GEORGE S. RODD.
